Geo. H. Noble

United States Patent Office.

GEORGE H. NOBLE, OF LOWELL, MASSACHUSETTS, ASSIGNOR TO HIMSELF
AND BENJAMIN T. MILLS, OF SAME PLACE.

Letters Patent No. 76,937, dated April 21, 1868.

IMPROVEMENT IN SPINDLE-BOLSTER.

The Schedule referred to in these Letters Patent and making part of the same.

TO ALL WHOM IT MAY CONCERN:

Be it known that I, GEORGE H. NOBLE, of Lowell, in the county of Middlesex, and State of Massachusetts, have invented certain new and useful Improvements in Bolsters for Spinning-Machines, of which the following is a full, clear, and exact description, reference being had to the accompanying drawing making part of this specification, in which—

Figure 1 is a central longitudinal section.

Figure 2, a side elevation as applied to a spindle.

Figure 3, a central longitudinal section considerably enlarged.

Figures 4 and 5 are end elevations of fig. 1.

Figure 6 is a central longitudinal section similar to fig. 1.

This invention consists in the employment of divided and tapering or conical bushings or linings, which fit a tapering hole in the outer shell, *d*, of the spindle-bolster, in combination with one or more oil-passages, *e*, and a dishing top to receive and convey the lubricating-substance to the annular oil-space, *b*, between the upper and lower portions of the tapering linings, *a*, of the bolster.

The principal object of the tapering bushings or linings *a* is to render the removal of old or worn bushings, and the replacing of new ones, easily and conveniently performed, and without removing the bolsters from the rail in which they are set.

The principal object in dividing the tapering bushings or linings *a*, is to obtain the oil-space *b* near the centre, as shown, so that the spindle will be better lubricated by an absolute pressure of oil from above, and passing through one or more oil-passages *e*, made in the substance of the bolster, or between the bolster proper and the lining, as in fig. 6, or downward and inward to the oil-space *b* and the spindle, which fills the central passage or interior of the lining above and below the oil-space *b*.

When the tapering bushings or linings have become so worn as to require replacing by new linings, they are easily and conveniently removed without injury to the bolsters, and without removing the bolsters from the rail which holds them.

I find, by experiment, that these improved spindle-bolsters can be made considerably cheaper than most of the other spindle-bolsters now in use, and, by reason of the lubricating-substance being conveyed to the spindle under absolute pressure or force, I have good reason for asserting both the spindle and the bushing or lining will endure much longer than in any of the ordinary spinning-machine bolsters now in use.

What I claim as of my invention, and desire to secure by Letters Patent, is—

The divided and tapering or conical bushings or linings, combined with a spindle-bolster, as described, the said bolster being provided with one or more oil-passages *e*, and a dishing top, to receive and convey the lubricating-substance to the oil-space *b* and the spindle, in the manner and for the purpose specified.
